UNITED STATES PATENT OFFICE.

ABBY ROGERS, OF SAN FRANCISCO, CALIFORNIA, ASSIGNOR OF ONE-HALF TO MARTIN NASH AND ONE-HALF TO W. G. HUTCHINS, BOTH OF SEATTLE, WASHINGTON.

FUEL MIXER FOR INTERNAL-COMBUSTION ENGINES.

Application filed December 11, 1920. Serial No. 429,946.

To all whom it may concern:

Be it known that I, ABBY ROGERS, a citizen of the United States, residing at San Francisco, in the county of San Francisco and State of California, have invented new and useful Improvements in Fuel Mixers for Internal-Combustion Engines, of which the following is a specification.

This invention relates to internal combustion engines, and has particular reference to a mixing device applicable to engines of this type.

The primary object of this invention is to provide a device of the above mentioned character adapted to be installed at the entrance of the intake manifold of internal combustion engines, particularly those used in automobiles and motor boats.

Another object of this invention is to provide a mixer including a base portion for a spindle which has mounted thereon a plurality of radial rotating blades functioning to break the gasoline into the finest particles as it comes from the carburetor in a vaporized form, and thus furnish a completely vaporized mixture.

Other objects and advantages of the invention will be apparent during the course of the following description:

In the accompanying drawings forming a part of this specification and in which like numerals are employed to designate like parts throughout the same,

Figure 1 is a side elevation of an automobile engine showing my device in position,

Figure 2 is a sectional view taken on the line 2—2 of Figure 3,

Figure 3 is a top plan view of the device, and

Figure 4 is a horizontal sectional view taken on the line 4—4 of Figure 2.

In the drawings wherein for the purpose of illustration is shown a preferred embodiment of my invention, the numeral 5 designates an apertured flanged portion of the carburetor, while the numeral 6 designates an apertured flanged portion of the manifold. Disposed between the two flanged portions and suitably retained therein by fastening elements 7, preferably bolts, is a base member 8 having a centrally located opening 9 and an internal beveled wall formed therein. Integrally formed with the base member 8, is an arm 10 terminating in a circular bearing 11 which is provided

with an internally threaded opening 12 adapted to receive a spindle 13 therein, threaded as shown at 14.

The numeral 15 designates a cap adapted to be detachably fastened to one extremity 60 of the spindle. Disposed between the bearing 11 and the cap 15, and loosely mounted on the spindle for rotation thereon, is a rotary element including a hub portion 16 and a plurality of radial blades or fan shaped 65 mixers 17. The blades are angularly disposed on the supporting hub and are so formed that vapors contacting therewith will tend to whirl outwardly after being thoroughly mixed and will more surely contact with the heated walls of the intake pipe and expand outwardly, thus producing the greatest possible heating effect before reaching the engine.

For the purpose of applying moisture to 75 the device, an angular tubular element 18 extending from the radiator enters an opening 19 formed in the base member 8, and thus serves to allow steam coming from the radiator to supply the moisture above 80 referred to.

It will be obvious that the blades are so proportioned that the diameter of the blades conform to the opening formed by the restricted wall of the base member, and thus 85 the full effect of the incoming passing currents of gas will be felt on the blades and directed there against through the medium of the beveled wall of the base member 8. By reference to Figure 2, it will be noted 90 that the hub portion 16 with its radial blades is accurately centered in the intake pipe and thus a proper centering of the fans is attained.

In the construction of the device, as far as 95 possible, the finest steel is employed, in order that the highest temperature may be obtained, and the fouling and corroding of the parts may be minimized.

From the description taken in connection 100 with the drawings, it will be obvious that I have provided a mixer comparatively economical in manufacture, simple in construction, compact in the arrangement of its parts, and a mixer which is applicable to 105 standard types of engines without materially altering the construction thereof, and a device which serves to afford complete combustion, at the same time minimizes the use of fuel.

It is to be understood that the form of my invention, herewith shown and described, is to be taken as a preferred example of the same, and that various changes in the shape, size and arrangement of parts may be resorted to without departing from the spirit of the invention, or the scope of the subjoined claim.

Having thus described my invention, I claim:

A device of the character described, comprising an apertured base member, an arm extending into the aperture formed in said

base and terminating in a bearing, a spindle mounted in said bearing, a rotary element 15 provided with radial blades and adapted to rotate on said spindle, means entering said base member for the purpose of distributing moisture to the blades of said rotary element, means for retaining said rotary element on said spindle, said aperture on said base member being tapered in such a manner that its smallest diameter is equal to the diameter of said rotary member.

In testimony whereof I affix my signature.

ABBY ROGERS.
